BRACKET FOR SUPPORTING SHADE ROLLERS AND CURTAIN POLES

Filed June 16, 1921

Inventor:
George Wousawicz
By George & George
A. Horneys

UNITED STATES PATENT OFFICE.

GEORGE WONSOWICZ, OF FORKS, NEW YORK, ASSIGNOR OF ONE-HALF TO HENRY J. RALICKI, OF FORKS, NEW YORK.

BRACKET FOR SUPPORTING SHADE ROLLERS AND CURTAIN POLES.

Application filed June 16, 1921. Serial No. 478,044.

To all whom it may concern:

Be it known that I, GEORGE WONSOWICZ, a citizen of Poland, residing in Forks, in the county of Erie and State of New York, have invented new and useful Improvements in Brackets for Supporting Shade Rollers and Curtain Poles, of which the following is a specification.

This invention relates to a bracket for supporting window dressings, such as the rollers of shades and the poles of curtains. It has for its object the provision of such a bracket which permits of mounting curtain poles and window shades of varying length in windows of different widths without requiring any alteration in the construction of the bracket.

In the accompanying drawings:

Figure 1 is a horizontal section of a window equipped with my improved brackets. Figure 2 is a side elevation of the same. Figure 3 is a fragmentary vertical longitudinal section, taken on line 3—3, Fig. 1. Figure 4 is a vertical section, on an enlarged scale, taken on line 4—4, Fig. 3. Figure 5 is a vertical section, on an enlarged scale, taken on line 5—5, Fig. 1. Figures 6, 7, 8 and 9 are perspective views of the main elements of my improved bracket.

Similar characters of reference refer to like parts throughout the several views.

In the window frame shown in the drawings, the upright stiles 10 are provided with outer vertical faces 11 upon which the brackets, which embody my improvements, are mounted. Inasmuch as the two brackets of a pair for supporting a shade roller 12 and a curtain rod or pole 13 are identical in construction, the following description of one will apply to both of them:

Each of these brackets comprises a fixed supporting member, a rear or inner body section and a front body section. The supporting member comprises a horizontal longitudinal guide arm 14 which is preferably slotted, as shown at 15, for reducing its weight and at its inner end this guide arm is provided with a rearwardly projecting lug 16 which is secured to one of the upright faces 11 of the window frame, by means of screws 17, as shown in Figs. 1, 2 and 4.

Each of the inner body sections comprises an upright longitudinal foot 18 which engages with the front side of the guide arm

14 and is capable of sliding horizontally and lengthwise thereon. The guide arm is embraced on its rear side by means of a clip 19, which is also slidable lengthwise and horizontally on the guide arm 14 and is connected at its opposite ends with the foot of the inner body section by means of bolts 20 which latter, upon being tightened, cause the inner body section to be securely held against movement on the supporting member, after the inner body section has been shifted into the required position to suit the relative dimensions of the window and the shade roller and curtain pole, which are to be mounted. On its inner part the foot 18 of each inner body section is provided with a forwardly projecting lug 21 upon which one end of the shade roller is adapted to be mounted in any suitable and well known manner. On the outer part of the foot 18 of the inner body section, the same is provided with a forwardly projecting arm 22 which latter is provided at its front end with a horizontal longitudinal guide bar 23.

The front body section 24 is provided at 25 its front end with a socket 25 which is adapted to receive one end of the curtain pole and on its rear part with an adjusting sleeve 26 which is adjustable horizontally and lengthwise on the guide bar 23 for adapting the socket 25 to the length of the curtain pole. After the front body section has been shifted into its proper position the same is rigidly held in place on the rear body section by means of a clamping screw 27 arranged on the sleeve 26 and engaging with the guide bar 23. The outer end of the front body section is preferably provided with an ornamental part, such as a ball 28.

In applying this bracket to a window the supporting members 14 are first secured to the opposite faces 11 of the window frame, then the rear body sections are secured to the supporting members in such a position that the lugs 21 will receive the pivots or stems on opposite ends of the shade roller and then the front body sections are adjusted horizontally on the rear body sections to suit the length of the curtain pole which is to be used, it being understood that the parts, after such adjustment, are securely held in place by tightening the clamping devices associated therewith.

This bracket in addition to being useful for mounting shade rollers and curtain poles

of varying lengths on windows of varying width, is also neat in appearance, so that it does not detract from the appearance of the dressings of a window, it is capable of being produced at relatively low cost and the adjustment of the same can be effected easily and conveniently.

I claim as my invention:

1. A bracket for a window dressing comprising a base having a horizontal longitudinal supporting arm and a lug projecting rearwardly from said arm and adapted to be secured to a window frame, a bracket section having a foot engaging with the front side of said arm and slideable horizontally thereon, a clip embracing the rear side of said arm and slideable horizontally thereon, and bolts connecting the ends of said clip with said foot above and below said arm.

2. A bracket for a window dressing comprising an inner body section having an inner lug adapted to support a shade, and an outer arm provided with a horizontal longitudinal guide bar, which projects away from said lug; an outer body section having a rear sleeve which slides on said bar and a front socket adapted to receive a curtain pole, a clamping screw arranged on said sleeve and engaging said bar, a base adapted to be secured to a window frame and provided with a horizontal supporting arm which engages with the rear side of said inner body section, a clip embracing the rear side of said supporting arm, and bolts connecting said clip with said inner body section above and below said supporting arm.

GEORGE WONSOWICZ.
